Primary Examiner — Mark A Goodwin*Assistant Examiner* — Harold E Blackwell, II**CLAIM**

The ornamental design for a square extension form as shown and described.

DESCRIPTION

FIG. 1 is a top perspective view of a square extension form, showing my design;

FIG. 2 is a bottom perspective view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof; and,

FIG. 8 is a bottom view thereof.
